INVENTOR

Clyde L. Knott.

UNITED STATES PATENT OFFICE.

CLYDE L. KNOTT, OF BEVERLY, MASSACHUSETTS, ASSIGNOR TO UNITED SHOE MACHINERY CORPORATION, OF PATERSON, NEW JERSEY, A CORPORATION OF NEW JERSEY.

OPERATOR'S CHAIR.

Application filed January 8, 1920. Serial No. 350,121.

To all whom it may concern:

Be it known that I, CLYDE L. KNOTT, a citizen of the United States, residing at Beverly, in the county of Essex and State 5 of Massachusetts, have invented certain Improvements in Operators' Chairs, of which the following description, in connection with the accompanying drawings, is a specification, like reference characters on 10 the drawings indicating like parts in the several figures.

This invention relates to chairs for use in factories and, particularly, to chairs which may be secured in position adjacent, 15 or attached to, factory machines and which may be adjusted to suit the requirements of each individual operator or class of work and then be folded underneath the machines when not in use.

20 An object of the invention is to produce a chair of this type which will be especially useful in shoe factories in connection with various shoe making machines.

A feature of the invention consists in 25 a novel foot rest which is adjustable relatively to the seat to accommodate operators of different stature and which is so constructed and arranged that it does not need to be readjusted when the seat is 30 raised, lowered or swung toward and from the machine for different kinds of work.

Other features of the invention consist 35 in improved means which, without sacrifice of general utility, allow the chairs to be applied readily to existing machines without altering said machines and in so constructing the chairs that they may be securely fastened to such machines and still fold compactly underneath the machines when 40 not in use.

Another feature of the invention consists 45 in providing a novel supporting means which, by engagement with the floor, will hold the chair securely in position whether the chair is in use or folded under the machine.

For convenience, in the following description and in the claims, the word "chair" will be used generically, as in the 50 foregoing, to indicate any organization having the characteristics herein set forth,

whether the invention be embodied in a stool, a chair, a bench or the like, and the word "seat" will be used to define the hereinafter described member 38 upon which 55 the operator sits.

In the drawings:

Fig. 1 is a perspective of the chair, shown attached to a clicking machine and in operative position;

Fig. 2 is a side elevation of the chair in folded position; and

Fig. 3 is a detail of construction showing the means for securing the chair to the machine.

Referring to the drawings, 10 is the usual cutting block which is supported on the bed 12 of the clicking machine. 14, 14 represents the supporting legs of the machine which are held together by the front tie-rod 16 and the rear tie-rod 18, each of which is a cylindrical member. The details of construction of the clicking machine are not pertinent to this invention and, accordingly, are not illustrated in the drawing. 75 Furthermore, the chair may be mounted upon numerous other types of machines and still be within the scope of the invention as defined in the claims.

One part of the chair consists of a swinging member or supporting column 20 which is bifurcated and which has two feet 21, 21 diverging from the lower portion thereof. At the end of each of these feet is a hook-shaped claw 22 for engagement with the tie rod 16. Each hook-shaped claw is held in engagement with the tie rod 16 by means of a retaining collar composed of two members 24 and 26 which may be secured together and clamped on the tie rod in any 90 desired longitudinal position by means of binding screws 28. Each claw has a side boss, substantially semi-circular in shape, which fits into an annular recess 30 in its retaining collar. By means of these complementally shaped surfaces on the claws and collars, each claw is prevented from being detached from the tie rod 16 although the claws are permitted to turn about the tie rod and collars because each boss is free 95 to move in its groove. Although only one retaining collar is shown in the drawings,

it will be understood that the entire chair may be adjusted laterally of the machine by locating the two collars in proper position along the tie rod 16.

5 A seat post 32 is mounted in telescopic engagement with the column 20 and carries at its upper end, each pivotally mounted on a transverse horizontal axis, a seat frame 34 and a seat bracket 36. The seat frame 10 carries a seat 38 of suitable size which is illustrated in dash lines in Fig. 1. A link 40 is pivotally mounted on the lower end of the column at 42. This link has mounted thereon a roller 44 which contacts with the 15 floor. One position of this link is determined by the engagement of an adjustable stop screw 46 with the lower end of the column 20. When in this extreme position, the link 40 serves as a support for the 20 column in operative position and the adjustment of the stop screw 46 provides for in-and-out or longitudinal adjustment of the seat. The seat bracket 36 is supported by a brace 48 which is adjustably and pivotally secured to the link 40 by a bolt 50, which may be located in any one of the set 25 of holes 52. The location of the bolt 50 determines the height of the seat and the amount of telescopic engagement between 30 the column 20 and the seat post 32. An adjusting screw 54 is mounted in the seat bracket and serves as a stop for the pivoted seat frame 34, which carries the seat 38, and thus determines the angular position 35 of the seat about a transverse horizontal axis.

A foot rest 56 is adjustably secured to the lower portion of the seat post 32 by a clamp screw 58. This is possible because of the 40 bifurcation of the column 20. It will be seen, because the seat and the foot rest are both secured to the seat post, that the foot rest 56 may be adjusted relatively to the seat 38 and this adjustment may remain constant if desired, irrespective of the adjusted height of the seat.

When it is desired to fold the chair beneath the machine, it may be done by pushing it forward so that the claws 22, 22, 50 swing about the tie rod 16. As this is done, the weight of the chair-seat and connected parts causes the link 40 to remain in contact with the floor and the seat post 32 to telescope into the column 20; the corner 60 of 55 the link finally coming into contact with the floor and causing the roller 44 to be lifted therefrom. The weight on the brace 48 tends to continue this swinging motion of the link, after the "dead center" is passed, 60 until the brace 48 comes into contact with the boss on the foot rest at 62. (This position is shown in Fig. 2.) Accordingly, the chair is locked in folded position by gravity because the link 40 is then swung beyond its 65 "dead center" and it can be released only

by a forward pull on the brace 48 which will cause the chair to return to the operative position illustrated in Fig. 1.

From the above description and drawings, it will be seen that this invention results in 70 a simple and efficient device for the purpose because it can be adjusted in every possible way to meet all of the requirements of an operator, no matter what his or her stature may be, and because it can be folded out of 75 the way when not in use.

Having thus described the invention, what is claimed as new and desired to be secured by Letters Patent of the United States is:—

1. A support for a chair comprising, in combination, a fixed pivot, a member mounted to swing about said pivot and adapted to carry a chair seat, and a link pivotally connected to said member and arranged to maintain said member in either of 80 two extreme positions by contact with the floor.

2. A support for a chair comprising, in combination, a swinging member adapted to carry a chair seat and a link pivotally connected to said member and arranged to maintain said member in either of two extreme positions by contact with the floor, said link being adjustable to vary one of 90 said positions so as to adjust the seat toward or from the machine.

3. A support for a chair comprising, in combination, a swinging member adapted to carry a chair seat and a link pivotally connected to said member and arranged to maintain the seat in either operative or folded position by contacting with the floor upon either one side or the other of a dead center.

4. A chair comprising, in combination, a 105 seat and a foot rest, said seat and said foot rest being mounted to swing as a unit about a horizontal axis and being vertically adjustable as a unit, and said foot rest being separately adjustable relatively to the seat. 110

5. A chair comprising, in combination, a supporting column having a tubular portion and a bifurcated portion, a seat post in telescopic engagement with said tubular portion, a relatively adjustable seat and foot 115 rest mounted on said seat post, said bifurcated portion being constructed and arranged to surround partially the portion of the seat post upon which the foot rest is mounted.

6. A mounting for adjustably securing a chair to a machine comprising, in combination, a cylindrical member on the machine, a hook-shaped claw connected with the chair and adapted to engage the cylindrical member and removable transversely therefrom, and a longitudinally adjustable collar on 125 said cylindrical member, said collar and said claw having complementally shaped portions constructed and arranged to retain the claw 130

in adjusted position on the cylindrical member and permit rotation between the claw and said member.

7. A folding chair for operators of machines, comprising, in combination, a seat, a seat post, a swinging member adapted to be pivotally connected to a machine and in

telescopic engagement with the seat post, a link pivotally connected to the column, and a brace pivotally connecting the seat post 10 and link.

In testimony whereof I have signed my name to this specification.

CLYDE L. KNOTT.
